US00D612423S

(12) **United States Design Patent**
Suero, Jr. et al.

(10) **Patent No.:** **US D612,423 S**
(45) **Date of Patent:** **** Mar. 23, 2010**

(54) **WRITING INSTRUMENT**

(75) Inventors: **Jose Suero, Jr.**, Boca Raton, FL (US);
Liu Luosen, Ningbo (CN)

(73) Assignee: **Office Depot, Inc.**, Boca Raton, FL (US)

(**) Term: **14 Years**

(21) Appl. No.: **29/311,105**

(22) Filed: **Dec. 23, 2008**

(51) **LOC (9) Cl.** **19-06**

(52) **U.S. Cl.** **D19/41**

(58) **Field of Classification Search** **D19/35, D19/36, 41-51, 53-57; 24/11 F, 11 P, 11 R; 401/52, 99, 100, 104-109, 192, 195, 196**

CLAIM

The ornamental design for a writing instrument, as shown and described.

DESCRIPTION

FIG. 1 is a front view of a writing instrument of my new design;

FIG. 2 is a left side view thereof, the right side view being a mirror image of the left side view;

FIG. 3 is a rear view thereof;

FIG. 4 is a bottom plan view thereof; and,

FIG. 5 is a top plan view thereof.

The broken lines showing the top in FIG. 5 are included for the purposes of illustrating environment and form no part of the claimed design.
